Primary Examiner — Katie Jane Stofko(74) *Attorney, Agent, or Firm* — Ryan T. Grace; Advent, LLP(57) **CLAIM**

The ornamental design for a cut potato product, as shown and described.

DESCRIPTION

FIG. 1 is a perspective view of a cut potato product; FIG. 2 is another perspective view thereof; FIG. 3 is a top plan view thereof; FIG. 4 is a bottom plan view thereof; FIG. 5 is a front elevation view thereof; FIG. 6 is a rear elevation view thereof; FIG. 7 is a left side elevation view thereof; and, FIG. 8 is a right side elevation view thereof. Portions of FIGS. 1 through 8 are shown in broken lines and dash-dot-dash boundary lines illustrating portions of the article that form no part of the claimed design.
